United States Patent Office.

A. HEGEMAN, JR., OF NEW YORK, N. Y.

Design No. 3,609, dated August 10, 1869.

DESIGN FOR A BRIDLE-BIT.

The Schedule referred to in these Letters Patent and making part of the same.

To all whom it may concern:

Be it known that I, A. HEGEMAN, Jr., of the city, county, and State of New York, have invented a new and original Design for Bridle-Bit; and I do hereby declare that the following is a full, clear, and exact description thereof, which will enable others skilled in the art to make and use the same, reference being had to the accompanying drawings, forming part of this specification, in which the drawing represents a perspective view of my new design for bridle-bit.

This invention relates to a new form of check-piece for bridle-bits of all kinds; and consists in the use of curved check-pieces A A, as shown.

These check-pieces are so formed that the ends of

each will be at about right angles to each other, and connected by a quarter circle, a, as shown.

On their ends are formed the eyes b b, for the head-stall-straps and reins, as usual.

The mouth-piece B is fitted with the ends into enlarged portions, C, of the check-pieces.

Having thus described my invention,

What I claim as new, and desire to secure by Letters Patent, is—

The design for bridle-bit herein set forth.

A. HEGEMAN, JR.
